CLAIM

The ornamental design for a mounting frame for touchpads, as shown and described.

DESCRIPTION

FIG. 1 is a front, right, top perspective view of a mounting frame for touchpads showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, right, bottom perspective view thereof;

FIG. 9 is a front, right, top exploded perspective view thereof; and,

FIG. 10 is a rear, right, bottom exploded perspective view thereof.
